UNITED STATES PATENT OFFICE.

JOSEPH PARADOWISH, OF BROCKTON, MASSACHUSETTS.

TROLLEY-POLE HEAD.

1,112,028.

Specification of Letters Patent. Patented Sept. 29, 1914.

Application filed June 5, 1914. Serial No. 843,131.

To all whom it may concern:

Be it known that I, JOSEPH PARADOWISH, residing at Brockton, in the county of Plymouth and State of Massachusetts, have invented certain new and useful Improvements in Trolley-Pole Heads, of which the following is a specification.

This invention relates to certain new and useful improvements in trolley pole heads.

10 An object of the invention is to provide a head for trolley poles with a trolley wire engaging portion to positively engage the wire and without the use of the usual trolley wheel.

15 A further object of the invention is to provide a head for trolley poles, in which the head is formed of a pair of pivoted arms of the plier type with an opening beyond the pivot point of the arms for the reception of a trolley wire and carrying at their outer ends opposed contact jaws with both ends of the contacting faces beveled to enable the same to pass a crossing wire.

20 With the above and general objects in view and others that will appear as the nature of the invention is better understood, the same consists in the novel construction, combination and arrangement of parts to be hereinafter more fully described and then 25 claimed, reference being had to the accompanying drawing by like characters designating corresponding parts throughout the several views, and wherein:—

Figure 1 is a side elevational view of a 30 trolley pole provided with my improved head. Fig. 2 is a top plan view of the same, and Fig. 3 is a detail end elevational view of the outer end of the head.

35 Referring more in detail to the accompanying drawing which shows the preferred embodiment of my invention, the numeral 10 designates a trolley pole of the usual construction and for the purpose of illustrating the use and operation of the device, 40 a trolley wire is indicated as at 11.

The pole head comprises in detail an arm 12 having the inner end 13 thereof of a shape similar to the pole 10 and is secured thereto by a suitable fastening means as at 45 14. The arm 12 is angularly bent at a point intermediate its ends as clearly shown in Fig. 1 and carries upon the outer end thereof a head 15 having the outer face ends thereof beveled as at 16. A bolt 17 passes through 50 the arm 12 at a point adjacent the outer end thereof and has pivotally mounted

thereon a second arm 18 continuing outwardly in a manner similar to the arm 12 and carrying upon its outer end a head 19 that engages the head 15 and is beveled as 55 at 20 on its opposite face ends opposed to the beveled portions 16. The arm 18 is angularly disposed as shown in Fig. 2 and is apertured adjacent its outer end as at 21 for the reception of a ring 22 carrying a 60 coil spring 23, the other end of said coil spring carrying a similar ring 22 mounted in the opening 24 provided in the arm 12. The spring tends to normally hold the heads 15 and 19 in contact with one another. For 65 the reception of the trolley wire 11, the arms 12 and 18 are provided with the jaw faces 25 through which passes the trolley wire, and it is to be noted that at all times the pole head will be in contact with the 70 wire due to the movement of the vehicle imparting continuous vibration to the arms.

The mechanism for separating the jaws 75 25 and heads 15 and 19 in positioning the same on the wire 11 comprises in detail an 80 arm 26 secured as at 27 to the end portion 13 of the arm 12 and angularly disposed as shown in Fig. 2, the outer end of the arm 26 formed to provide a housing 28 for the reception of a revolvably mounted sheave 29. 85 The end of the arm 18 is provided with an opening 30 for the reception of one end of a rope 31 which passes through the housing 28 and over the sheave 29 to a point adjacent the car.

90 In positioning the head upon the wire 11, the strain on the rope 31 will move the outer end of the arm 18 toward the sheave 29, which movement will cause the outer end of the arm 18 to move on its pivot 17 and 95 separate the heads 15 and 19 and the jaw faces 25. When the device has been properly positioned on the wire 11, the strain on the rope is released and the spring 23 in asserting itself will move inwardly the outer 100 end of the arm 18 to close the heads 15 and 19, with the jaws 25 inclosing the wire. By providing the front and rear ends of the heads 15 and 19 with opposed beveled faces, the device is permitted to freely pass a cross 105 wire or other obstruction.

While I have shown and described the preferred embodiment of my invention, I do not wish to confine myself to the exact details of construction shown, as various 110 forms, modifications and arrangements of the parts as shown may be had without

departing from the spirit and scope of the invention as claimed.

What I claim as new is:—

The combination with a trolley pole, of an angular arm secured to the outer end thereof, said arm carrying a head at its outer end, a second angular arm pivoted to the first-named arm and provided with a head in engagement with the first-named head, the front and rear ends of the opposing faces being beveled for a portion of their lengths, jaws on said arms inwardly of the heads, a spring connecting the inner ends of the arms and adapted to bring the

heads into contact, a third arm secured at one end to the first-named arm, a pulley revolubly mounted in the other end of said arm, and a rope passing over said pulley and connected at one end to the second-named arm for controlling the movement of said head.

In testimony whereof I affix my signature in presence of two witnesses.

JOZEPH PARADOWISH.
